POLISH CONTAINER

Carl F. Schmid, Park Ridge, Ill., assignor to Turtle Wax,
Inc., Chicago, Ill., a corporation of Illinois

Filed July 28, 1965, Ser. No. 86,335

Term of patent 14 years

(Cl. D58—17)

FIG. 2 is a side elevational view of the polish container illustrated in FIG. 1; and

FIG. 3 is a plan view of the polish container of FIG. 1. The side opposite that shown in FIG. 1 is identical thereto, and the bottom of the design is circular and substantially plain and unornamented.

I claim:

The ornamental design for a polish container, substantially as shown and described.
